UNITED STATES PATENT OFFICE.

JACOB A. NEWMAN, OF MADISON, WISCONSIN.

SNOWPLOW AND SHOVEL.

Application filed March 12, 1924. Serial No. 698,808.

To all whom it may concern:

Be it known that I, JACOB A. NEWMAN, a citizen of the United States, residing at Madison, in the county of Dane and State 5 of Wisconsin, have invented certain new and useful Improvements in Snowplows and Shovels, of which the following is a specification.

My invention relates to machines for 10 breaking up snow drifts and removing the snow from highways and streets by cutting the snow ahead of a plow or transverse bar parallel with the street and forcing it backward upon and past the same within reach 15 of an elevator; and the objects of my invention are, first, to assemble in practical working relation, cutting or digging members above and ahead of a horizontal bar or transverse platform, said members revolvably 20 attached to and operated by a transverse multiple crank shaft revolvably journaled within suitable bearings secured to the main frame of the device; second, to construct a frame with a bar or narrow platform extending across the front lower edge adapted 25 to receive the snow cut and forced backward by the cutting members and deliver it to an elevator; third, to provide an elevator which will take the snow from the bar and carry 30 it upward to an adjustable transverse conveyor from which it will be deposited on either side of the road as desired; fourth, to have the cutting members and elevators and conveyors driven from a power unit 35 mounted on the frame, but means provided by which they may be driven from the rotary power pulley upon the tractor which may be used to push the machine; fifth, to have the device hinged to the tractor and 40 means provided by which it may be raised at the front end, so as to remove the upper portion of deep drifts and then lowered to the road for removing the balance; and sixth, to mount wheels upon adjustable arms 45 at the front end of the frame to be used when moving the machine over open roads.

I attain these objects by the mechanism shown in the accompanying drawing in which—

- 50 Fig. 1, is a plan;
Fig. 2, is a left side elevation;
Fig. 3, is a rear end elevation.
Similar numerals refer to similar parts throughout the several views.
55 The frame comprises side rails 1 vertical side posts 2 with cap cross beam 2^a secured

to the upper ends thereof, inclined front corner posts 3 with cap plate 4 connecting the top ends, side beams 5 connected to the corner posts and extending backward to and 60 beyond the posts 2 for mounting a conveyor thereon, lower rear side braces 6 extending from the lower side rails 1 upward to the rear end of the side beams 5, lower front side braces 7 from the rails 1 forward to the corner posts 3, upper side braces 8 from front ends of beams 5 to the top of posts 2, upper front side braces 9 from intersection of side beams 5 and posts 2 to the top of the corner posts 3, cross beams 10 between the 70 side rails 1, with cross ties 11 between the beams 5. Two multiple crankshafts 12 and 13 are journaled in boxes 14 which are secured to the corner posts 3, said shafts have the crank arms disposed in alignment with 75 each other and of equal throw. Upon the wrist pins of the shafts, suitable bearing boxes 15 are disposed, with flanges 16 adapted to be secured to vertical beams or shovel handles 17, shovel blades 18 are secured to 80 and across the lower ends of each pair of handles, forming a downwardly and backwardly cutting or digging unit, any practical number of which may be employed on a machine. The two crank shafts 12 and 13 are revolvably connected together by suitable 85 transmission means, preferably sprocket wheels 19 and chain 20. A transverse bar or narrow platform 21 of sheet metal with upwardly extending flanges at each end is 90 located at the front end of the side rails 1 and bolted thereto, the front edge of the bar is parallel with the road and in operation just clears the same, but the rear edge is elevated sufficient to carry snow upward 95 and conduct it to an elevator. An elevator 22 extending from side to side of the frame and secured thereto, has its lower end located just back and under the bar 21 and its upper end backward and above the rear portion of side beams 5, and directly over a horizontal conveyor 23, whereby snow broken up by the shovels 18 and forced over the bar 21 will be carried up the elevator 22 dropped upon conveyor 23 and carried 100 to either side of the road by the conveyor, the motion of which can be reversed as will be hereinafter explained. A power unit, preferably a gasoline engine 24 is secured to a platform 25 on the top and across the rear end of side rails 1. A jack-shaft 26 is journaled in boxes 27 secured to the vertical 105 110

posts 2 and is revolvably operated from the engine by transmission means, preferably sprocket wheels 28 and 29 and chain 30. To the outer ends of the jack-shaft 26 outside of the frame (looking forward) sprocket wheels 31 are secured and similar wheels 32 are located on the outer ends of crank-shaft 12 and the two are revolvably connected by chains 33, thereby power is transmitted from the engine 24 to the shovels 18. Outside of the wheel 31 on the left end of the jack-shaft a sprocket wheel 34 is secured and a chain 35 leads upward to a similar wheel integral with a spur gear 36, both mounted revolvably on a stud-pin 36^a on the side of the elevator 22 the upper cross shaft of which is provided with a spur gear 37 which meshes with gear 36, thereby revolvably connecting the engine with the said elevator in proper relation to carry the snow upward. A shaft 38 is located under and across the beams 5 back of the vertical posts 2 and journaled in boxes 39, upon said shaft two bevel pinions 40 are loosely mounted and in mesh with a bevel gear 41 which is secured to a vertical shaft 42, at the top of the shaft 42 a miter gear 43 is secured which meshes with a similar gear 44 which is secured to the inner end of a horizontal shaft 45 carrying sprocket wheels 46 upon which the conveyor chains 47 of the conveyor 23 are disposed. A clutch knuckle 48 slidably mounted on the shaft 38 and adapted to engage jaws on the inner surfaces of the bevel pinions 40 provides a means for reversing the motion of the conveyor before referred to. A shifting fork 49 operably attached to the knuckle 48 and provided with a handle 50 is pivoted on a stud-pin 51 extending downward from the middle cross tie 11, said handle extending backward a distance desired for operating the clutch back of the machine. The said conveyor 23 is of common type, two lines of sprocket chain secured to the ends and under sides of cross slats, and is driven by sprocket wheels engaging the chains from the under side, the sprocket wheels as before explained to the cross shaft 38, which is operably connected intermediate its length to the jack-shaft by gears 52. At the rear side and right end beneath the bottom of the conveyor a length of toothed rack 53 is secured, which meshes with a spur pinion 54 which is loosely disposed on a stud-pin 55 secured adjacent the top of the angle plate 56, a universal coupling 57 is attached to the pinion 54 and a rod 58 extends backward for manually operating the conveyor either to the right or left for depositing the snow as desired. The side frame of the conveyor comprises side boards and sills with necessary cross beams and is secured to two round rods 59 which curve downward from the ends of the sills for a distance thence become parallel

to the sills, said rods are slidably disposed between rollers 60 revolvably mounted on pins 61 through the top portion of the angle plates 56 which are mounted on the top of the beams 5. It is therefore obvious that by turning the rod 58 the conveyor may be moved to the right or left side of the machine. It is also plain that by moving the handle 50 to the right or left, the movement of the conveyor will be reversed. Shoes 62 are provided at the under front ends of the rails 1. The truck wheels 63 mounted on an axle 64 secured between arms 65 adjustably pivoted to the rails, provide a means for transporting the machine over open roads.

Hinge beams 66 are connected to the rear ends of the rails for fastening a tractor back of the machine, and cables 67 attached to the posts 3 and over pulleys 68 when wound upon a winch will raise the front end of the machine hinged at 69.

To operate the machine, fasten by the hinge beams 66 to the front end of a tractor and push into the snow, start the engine 24 which may have a clutch interposed between it and the jack-shaft if desired, then the cutters will cut downward and backward moving backward any snow or ice encountered thence the snow will pass upward on the elevator 22 and be dropped to the conveyor 23 and carried to the side of the road. To be used to operate the machine in case the engine fails, a pulley or sprocket wheel 70 is secured to the extreme right end of the jack-shaft 26.

Having thus described my invention, I claim:

1. In a snow removing device, a frame comprising base sills and cross beams, inclined posts at the front corners connected at the top by a cap plate, two multiple crank shafts journaled in boxes secured to the posts, shovel handles pivotally connected to wrist-pins on both the crank-shafts, the crank arms on the shafts in alignment with each other and oppositely disposed, the crank-shafts revolvably connected at both ends by wheels and chains, shovel blades located at the bottom of the handles, adapted to pass downward and backward through the snow in class relation to a cross bar or narrow transverse platform at the front end of the sills when the crank-shafts are revolved, in combination with an elevator and conveyor for carrying the snow to the side of the road, and transmission means for revolvably operating the same.

2. In a snow removing device, a frame comprising sills and cross beams and suitable braces, digging members revolvably mounted at the front end, an elevator adapted to carry snow loosened by the digging members, upward and backward to a conveyor, a transverse conveyor under the upper end of the elevator, with means for

moving the conveyor cross-wise of the machine; said conveyor supported by longitudinal rods slidably disposed between rollers mounted on pins in angle plates secured on the top of the side beams of the frame, a power unit mounted on the sills, revolvably connected to a jack-shaft journaled in boxes secured to the frame and transmission means whereby the power unit will operate
10 all the revoluble members, a pulley wheel at one end of the jack-shaft for connecting auxiliary power, cables attached to the front

upper end of device passing over intermediate pulleys on the same and wound upon a windlass back of the machine, in combination with hinge beams attached to a tractor in the rear, for elevating the front end of the machine substantially as described. ¹⁵

In testimony whereof I affix my signature in the presence of two subscribing witnesses.

JACOB A. NEWMAN.
